UNITED STATES PATENT OFFICE.

ROY A. WEAGANT, OF NEW YORK, N. Y., ASSIGNOR, BY MESNE ASSIGNMENTS, TO
RADIO CORPORATION OF AMERICA, A CORPORATION OF DELAWARE.

APPARATUS FOR RECEIVING RADIOSIGNALS.

1,425,154.

Specification of Letters Patent. Patented Aug. 8, 1922.

Application filed December 13, 1917. Serial No. 206,883.

To all whom it may concern:

Be it known that I, ROY ALEXANDER WEAGANT, a citizen of the United States, residing at Douglas Manor, county of Queens, city and State of New York, have discovered certain new and useful Improvements in Apparatus for Receiving Radiosignals, of which the following is a specification.

10 My invention relates to the art of radio signaling and has as its principal object the provision of novel and improved receiving apparatus for reducing or preventing static interference.

15 My present invention is based upon observations made by me and set out at some length in my prior application No. 157,594, wherein I have stated that the so-called "static" disturbances act as though such disturbances were caused by electro-magnetic waves or impulses propagated perpendicularly to the surface of the earth, and almost without horizontal components. Whether or not this is a correct statement of the facts,

25 I find that by proceeding on this assumption and by screening an aerial collector as by placing such collector beneath a metallic or other conducting screen, I am able to very largely overcome the interference with the reception of radio signals caused by the most objectionable forms of atmospheric disturbances, the static waves being absorbed by the screen and the collector consequently shielded therefrom. On the other hand,

30 commercial radio signal waves travel horizontally or have a large horizontal component of motion, so that by leaving the collector unscreened on the side from which the signal waves approach the receiving station there is practically no change in the effect of the signal waves on the receiving apparatus. I have found, moreover, in practicing this invention that the effectiveness of the screen in absorbing and preventing the passage of static waves is increased if the screen is grounded. Experience shows also that grounding the screen does not decrease the effect of the signal waves on the receiving apparatus. This is in accordance with my

45 observations to the effect that commercial signal waves extend a material distance beneath the surface of the ground with small diminution in strength. This fact is set out also in my application for apparatus 50 for preventing static interference in radio

signaling, Serial Number 206,724, filed December 12, 1917.

In the drawing accompanying and forming a part of this specification, Figure 1 is a diagrammatic perspective view of an apparatus embodying one form of my invention, and Figure 2 is a similar view of a modification.

Referring more particularly to the drawing, 1-1 are posts of any convenient height provided with guy wires such as 2. On the upper ends of the posts 1 are supported in any convenient manner conducting cross-bars such as 3, between which are supported a number of conducting or metallic elements such as 5, forming a screen against the vertically moving component of electromagnetic waves or those which act as if propagated in a vertical direction. The members 5 are shown in the form of parallel wires, but it will be understood that this is not essential. The cross-bars 3 are shown as grounded by means of ground wires such as 6.

Beneath the screen 5 I have shown a non-conducting frame such as 7, which may be supported in a substantially vertical position in any convenient manner as by guy wires such as 8. Suspended within the frame 7 by any convenient means such as the wires 9, is a loop or coil collector 10 arranged substantially in the plane of the frame 7, the collector being insulated from the ground. Preferably the horizontal projection of said screen overlaps and extends beyond the horizontal projection of the collector on all sides. The ends of collector 10 are connected to a coupling coil 11. A coil 12 is associated with coil 11 in the usual manner to impress the received impulses upon a local circuit 13 containing a vacuum valve detector 16. Such detector 16 is well known, but is described below in some detail as a matter of convenience. As shown, the circuit 13 comprises a variable condenser 14 in parallel with the wires of the circuit 13, a condenser 15 in series with the coil 12, the capacity 15 being connected to the grid of the vacuum valve detector 16. A local heating battery for the filament of the detector is shown at 17, the plate or cold electrode of the valve detector being shown at 18. The battery 19 is connected with the coil 12 through the plate and filament of the detector in the usual manner, a telephone 20 110

being shown in series with the battery 19 and a variable condenser 21 in shunt with the telephone 20. An inductance 22 and capacity 23 are connected in parallel to the battery 19 and telephone 20.

5 In Fig. 2 I have shown a modified form of screen composed of three conducting plates such as 25, arranged in the form of an inverted trough with open ends and supported on insulating structures, such as 26. Connected to the middle of the lower edge of each of the vertical plates 25 is a grounded circuit comprising a variable inductance 27 and variable capacity 28, whereby the relation of the currents in the screen may be maintained symmetrical in all respects with relation to any antenna or collector beneath the screen, so that the currents in the screen may not of themselves affect the collector.

10 The detector and indicator circuits associated with the collector shown in Fig. 2 may be the same as those shown in Fig. 1.

15 20 25

While I have herein specifically illustrated and described only a loop antenna, this particular form is in no wise essential to the

practice of my invention which my experiments show can be practised with any of the forms of antennæ now in commercial use. Moreover, I do not find it necessary to arrange the loop antenna in a vertical plane 30 when such is used, although the vertical arrangement is preferable.

Having thus described my invention, I claim:

1. In a radio signalling apparatus, the combination with an antenna of an open ended inverted trough-shaped screen for protecting the collector from electromagnetic waves moving vertically downward and along a given horizontal line in either direction. 35

2. In a radio signalling apparatus, the combination with a collector of an open ended inverted trough-shaped screen covering said collector above and on two sides, and adjustable grounded circuits connected to the lower edges of said screen at the mid-points thereof. 40 45

ROY A. WEAGANT.
